US0D1073016S

(12) **United States Design Patent** (10) **Patent No.:** **US D1,073,016 S**
(45) **Date of Patent:** **** Apr. 29, 2025**

(54) **HANDSHOWER**

(71) Applicant: **GROHE AG**, Hemer (DE)

(72) Inventors: **Duarte Salvador**, Düsseldorf (DE);
Tim Prigge, Düsseldorf (DE); **Patrick Speck**, London (GB)

(73) Assignee: **GROHE AG**, Hemer (DE)

(**) Term: **15 Years**

(21) Appl. No.: **29/884,396**

(22) Filed: **Feb. 10, 2023**

(30) **Foreign Application Priority Data**

Aug. 10, 2022 (EM) 009145493-0005
